UNITED STATES PATENT OFFICE

VERGIL O. GREENE, OF KANSAS CITY, MISSOURI

DESIGN FOR A RADIATOR ORNAMENT

Application filed April 29, 1931. Serial No. 39,657. Term of patent 3½ years.

To all whom it may concern:

Be it known that I, VERGIL O. GREENE, a citizen of the United States, residing at Kansas City, in the county of Jackson and State of Missouri, have invented a new, original, and ornamental Design for a Radiator Ornament, of which the following is a specification, reference being had to the accompanying drawings, forming a part thereof.

I claim:

The ornamental design for a radiator ornament, as shown.

VERGIL O. GREENE.
